UNITED STATES PATENT OFFICE

ERNIE GROESBECK, OF OSHKOSH, WISCONSIN

ROTARY PUMP OR ENGINE

Application filed May 26, 1925. Serial No. 33,029.

This invention relates to rotary pumps or engines, and more particularly to an apparatus of this character comprising a casing, a rotor mounted therein, an abutment carried by the rotor, and a movable gate adapted to cooperate with the abutment and form chambers within the casing.

An object of the invention is to provide an apparatus of this character of comparatively few parts, possessing compactness, simplicity and durability.

A further object is to provide improved means for actuating the gate whereby it is raised on each revolution of the rotor to permit the abutment to pass it.

A further object of the invention is to provide a construction of a rotary member which may be employed either in pumps or engines.

20 In the accompanying drawings, I have shown several embodiments of the invention. In this showing:

Figure 1 is a front elevation,

Figure 2 is a detail perspective view of 25 the gate and a portion of the operating means therefor,

Figure 3 is an end elevation,

Figure 4 is a vertical sectional view on line 4—4 of Figure 1,

30 Figure 5 is a similar view on line 5—5 of Figure 3,

Figure 6 is a similar view on line 6—6 of Figure 4,

Figure 7 is a front elevation of another 35 form of the invention,

Figure 8 is an end elevation,

Figure 9 is a vertical sectional view on line 9—9 of Figure 7,

40 Figure 10 is a front elevation of a rotary steam engine constructed in accordance with the invention,

Figure 11 is an end elevation,

Figure 12 is a perspective view of the gate and a portion of the actuating means there- 45 for,

Figure 13 is a detail sectional view of a portion of the rotor and the gate showing the exhaust passage through the gate,

50 Figure 14 is a vertical sectional view on line 14—14 of Figure 10,

Figure 15 is a detail perspective view of the governor actuated mechanism, and the governor valve, and,

Figure 16 is a horizontal sectional view on line 16—16 of Figure 14.

Referring to Figures 1 to 6 of the drawings, wherein I have shown one form of the invention adapted to operate as a pump, the apparatus consists of a suitable casing 1 which is circular in vertical cross section, as shown in Figure 4 of the drawings, and which may be supported on a suitable base 2. As shown, the casing is closed by end plates 3, secured thereto by means of bolts 4. It is further provided with a central vertical partition 5, forming two compartments. A main shaft 6 extends through the center of the casing and is mounted in suitable bearings 7 carried by the end plates. These bearings may be provided with suitable packing 8 retained in place by means of packing glands 9. A rotor 10 is mounted in each section of the casing and each of the rotors is provided with an abutment 11, the outer face of which is adapted to contact with the interior wall of the casing, as shown in Figure 4 of the drawings. The rotors are secured to the shaft to revolve therewith by means of keys 12 and, as shown in Figures 5 and 6 of the drawings, are arranged with the abutments 11 opposite each other or 180 degrees apart. The side faces of the rotors are provided with packing rings 13 to prevent leakage and these rings are forced outwardly toward the end walls and the center partition by means of suitable springs 14 disposed at intervals throughout the rotor, as shown in Figure 5 of the drawings.

One side of the casing is provided with an extension 15 having a center port or passage 16 and adapted to be connected to an intake pipe 17. The top of the casing is provided with an extension 18, forming a chamber 19 and this chamber communicates with the interior of the casing through an opening 20. The chamber 19 is provided with an outlet or discharge opening 21. A shaft 22 extends through the chamber 19 substantially parallel to the main shaft 6 and the movable gates are mounted on this shaft and are adapted

to normally extend into the interior of the casing through the openings 20. As shown, a sleeve 23 is keyed to the shaft by means of a key 24, and this sleeve carries on arm 25 having a plate 26 on its outer end which plate is of substantially the same width as the width of one of the sections of the casing and serves as a gate to form a chamber within the casing between the gate and the abutment 11. The gate is provided with a packing strip 27 in its face normally forced outwardly by means of a spring 28 to engage the adjacent surface of the chamber 19 and prevent leakage of fluid from the inlet side of the casing into the chamber 19.

Suitable means are provided for raising the gate to the position shown in Figure 4 of the drawings, at each revolution of the rotor to permit the abutment 11 to pass. As shown, the main shaft is provided with a cam 29, and this cam is adapted to engage a roller 30 carried by a valve tappet rod 31. This rod passes through an opening in a bracket or arm 32, carried by the end plate (see Figure 5) and is prevented from turning by means of a pin or set screw 33, received in a groove 34 of the rod. As shown, the cam is secured to the shaft by means of a key 35 and is provided with one high point 30 to raise the rod once to each revolution of the shaft. A sleeve 36 is keyed to the shaft 22 by means of a key 37, and this sleeve carries an arm 37 which serves as a crank and is provided with a lateral extension 38 on its outer end. The crank portion 37 of this arm is adapted to be engaged by the reciprocating rod 31 to oscillate the shaft 22 and thus raise the gate 26. The gate is normally retained in lowered position by means of a spring 39 carried by a bolt 40 which passes through an opening 41 in the lateral extension 38 of the crank and is received in the arm or bracket 32. The upper end of the spring engages a nut 42 arranged on the bolt 40 to permit the tension of the spring to be adjusted.

In the form of the invention shown in Figures 7 to 9 of the drawings, the construction and operation is essentially the same. In this instance, the pump is provided with an inlet pipe 43 and an outlet pipe 44 communicating with a valve chamber 45 arranged on the top of the pump casing. The pivoted gate 26 is replaced by a sliding gate 47, one of which is provided for each section of the pump casing. These gates are controlled by means of rods 48 slidably mounted in brackets 49 carried by the end plates and provided with rollers 50 adapted to engage the cams 29.

An arm or bracket 51 is arranged above the bracket 49 and is adapted to support a pivoted tappet rod 52 which is pivotally mounted in the end of the arm, as at 53. The upper end of the gate 47 carries a rod 54 which is adapted to receive a grooved collar 55 retained in position by means of a nut 56. The

arm 52 is provided with a yoke 57 on its free end, adapted to be received in the grooved collar 55. As shown, the arm also carries a bolt 58 having an enlarged head 59 adapted to be engaged by the rod 48.

The valve chamber 45 is divided into an inlet chamber 60 on one side of the gate and an outlet chamber 61 on the other side. The inlet chamber is provided with a valve seat adapted to be engaged by a valve 62 mounted on a stem 63 and the valve stem projects from the casing and is provided with a coil spring 64 retained in position by nuts 65 and adapted to normally retain the valve in closed position. This valve is adapted to be opened by suction and the gate is provided with a groove or passage 66 in its face through which the fluid flows to the pump casing. On the outlet side, there is provided a valve 67 mounted on a valve stem 68 and adapted to be opened by pressure. The valve stem is provided with a reduced portion having a coil spring 69 arranged thereon which is compressed when the valve is opened and normally retains the valve in closed position. The adjacent face of the gate is likewise provided with a groove or passage 70.

In Figures 10 to 15 of the drawings, I have shown the invention applied to a steam engine. As the construction of the main casing, the rotor and the abutments is substantially the same, as heretofore described, a further description thereof is deemed unnecessary. In this instance, I provide a cam 71 which is in reality a pair of cams and is provided with two high points 72 and 72', one of which is adapted to operate the gate and the other adapted to operate the throttle valve. The cam 72' is adapted to reciprocate a rod 73 mounted in an opening in a bracket 74 on the side of the casing and this rod is adapted to engage an arm or crank 75, formed on a sleeve 76, loosely mounted on a shaft 77. The sleeve is provided with a second arm or crank 78 which is connected to an arm or crank 79 by means of a pin 80. The throttle valve consists of a cylindrical member 81 arranged in an intake chamber 82 and a separate throttle valve is arranged on each side of the partition 5 to control the flow of steam to each section of the casing.

As shown, the valve is provided with a reduced projecting portion 83 to which the arm 79 is secured so that the valve will be oscillated when the sleeve 76 is oscillated by the reciprocating rod 73. A suitable packing gland 84 is arranged around the projecting portion of the valve.

As shown in Figure 14 of the drawings, the inlet chamber is provided with a central passage 85 connected to an inlet pipe 86 and the throttle valve is arranged at the inner end of this passage and provided with a port or passage 87 adapted to communicate with an opening 88 in the main casing.

- A governor valve is arranged in the passage 85 exteriorly of the throttle valve. As shown, the governor valve consists of substantially cylindrical end portions 89 connected by arcuate or segmental portions 90 and provided with stub shafts 91 at each end. One of the cylindrical portions is provided with an eccentric opening 92 adapted to receive a pin 93 arranged in an elongated slot 94 on the lower end of a governor rod 95. The governor is of the ball type, provided with the usual balls 96 connected to a movable plate 97, and a bevel gear 98 by means of arms 99. The governor is driven from the main shaft by means of a belt 100 passing over a pulley 101 on the main shaft and a pulley 102 on a shaft 103. The shaft 103 is provided with a bevel gear 104 meshing with the bevel gear 98.
- The gate employed in the steam engine construction is operated in substantially the same manner as the sliding gate 47 in the form of the invention shown in Figures 7 to 9 of the drawings. As shown, the gate consists of a main body portion 105 mounted in a chamber 106 and this chamber is provided with an opening 107 to which the exhaust or discharge pipe is connected. The rear face of the gate is provided with a groove 108 through which the exhaust pipe is connected to the casing at all times. The opposite face of the gate is provided with a packing strip 109 which is retained in engagement with the inner face of the chamber 106 by means of a spring 110. The upper end of the gate is provided with a rod 111 adapted to receive a grooved collar 112 retained in position by means of a nut 113. A rod 114 is mounted in a second opening in the bracket 74 and is adapted to be reciprocated by the cam 72'. This rod is adapted to actuate an arm 115 pivoted as at 116 to a bracket 117. The inner end of the arm is provided with a yoke 118 received in the grooved collar 112. The arm is normally retained in lowered position by means of a coil spring 119 carried by a rod or bolt 120 which passes through an opening 121 in the arm. Nuts 122 may be arranged on the bolt to permit adjustment of the spring.
- In the operation of the form of the invention shown in Figures 1 to 6 of the drawings, the rotor revolves in the casing and upon each revolution, the gate 26 raises, as indicated in Figure 4 of the drawings, to permit the abutment or piston 11 to pass. As soon as the piston passes the gate, the roller 30 passes off the high portion of the cam 29 and the spring 39 returns the shaft 22 to its original position, permitting the gate to be lowered through the opening 20 into the casing. As shown in Figures 5 and 6 of the drawings, the gates are independently operated by means of separate cams arranged on opposite ends of the shaft and disposed at 180 degrees from each other. When the gate

is lowered and the rotor continues to revolve, a partial vacuum is created in the casing in the space between the gate and the abutment 11. Fluid then flows through the inlet pipe 17 into the casing behind the abutment and the fluid that has entered on the past revolution and is in front of the abutment is forced out through the chamber 19 to the outlet opening 21.

In the form of the invention shown in Figures 7 to 9 of the drawings, the operation is essentially the same, the gate in each section of the pump casing being raised through its cam 39 to permit the piston or abutment 11 to pass. The partial vacuum created in back of the piston or abutment and in the inlet chamber unseats the valve 62 against the tension of the spring 64 and permits fluid to enter from the inlet pipe. Similarly, the fluid forced into the outlet chamber through the port or passage 70 in the gate unseats the valve 67 by pressure to permit the fluid to escape through the discharge pipe 44. The raising of the gate on each revolution of the rotor is accomplished through the reciprocating rod 48 which raises the arm 52 and this arm is returned to normal position by means of a spring (not shown) similar to the spring 39.

In the operation of the device as a steam engine, the gate 105 functions in the manner just described and is caused to raise at the proper time by the cam 72', rod 114, and pivoted arm 115. The arm is returned to normal position to lower the gate by means of the spring 119. The throttle valve oscillates through a portion of a circle to supply a quantity of steam to the casing when the parts are in the position shown in Figure 14 of the drawings just after the abutment has passed the inlet opening 88. This is accomplished by oscillating the crank or arm 79 on the end of the throttle valve through the provision of the arms 75 and 78, the loosely mounted sleeve 76, the rod 73 and the cam 72. The governor valve operates in the usual manner to cut down the size of the passage by oscillating the valve until the segmental portion 90 closes or partially closes the passage 85.

It is to be understood that the forms of my invention herewith shown and described are to be taken as preferred examples of the same, and that various changes in the shape, size, and arrangement of parts may be resorted to without departing from the spirit of the invention or the scope of the subjoined claim.

I claim:

A device of the character described comprising a cylindrical casing, a partition arranged in said casing to divide it into two cylindrical sections, a solid cylindrical rotor mounted in each section of said casing, and having its periphery spaced from the walls 125 130 135

of the casing, a main shaft extending through said casing and carrying said rotors, rigid radial abutments carried by and integral with said rotors at substantially 5 180° from each other, an outlet chamber communicating with each section of said casing, gates mounted in said outlet chambers, each gate being arranged to project into different sections of said casing to engage the periphery of said rotors, said casing being provided with an inlet opening forwardly of said gates whereby fluid enters 10 between the casing and the rotors on one side of said gates and flows into said outlet chamber on the opposite side of said gates, said gates being provided with pivoted arms, an auxiliary shaft arranged to operate said arms, cranks secured to said last named shaft, tappet means for actuating said 15 cranks, and cams carried by the main shaft for actuating said tappet means.

In testimony whereof, I affix my signature.
ERNIE GROESBECK.
